QUICK-ACTING REGULATOR OF THE VIBRATING TYPE

Original application filed May 24, 1928, Serial No. 280,287, and in Germany June 1, 1927. Divided and this application filed May 2, 1929. Serial No. 359,980.

For regulating train-lighting generators to keep the voltage or the current constant, both regulators of the vibrating type and of the carbon compression type are used. Both

5 types of regulators have considerable disadvantages which closely circumscribe their use in spite of their great mechanical simplicity.

The disadvantage with the trembler regulator is, that the trembler contacts are subject to rapid destruction, owing to their being excessively stressed. This is due to the fact that, when the contacts are being opened, there is too great a difference in 10 voltage between the contacts. This difference in voltage is due to the rigid resistance connected up parallel to the trembler contacts. Consequently, each time the contacts are opened an arc is formed, the intensity of 15 which depends on the strength of the excitation current and the drop in voltage. Although by using a resistance having a number of steps the forming of sparks by the contacts is diminished, it is still far too great 20 when a considerable excitation current flows, so that in this case as well the life of the vibrating contacts is very short. In the case of the carbon compression type regulator, the disadvantages make themselves felt in this 25 way, that the ohmic resistance of the carbon column is not constant, but is subject to considerable variations in the course of time according to the structure of the carbon. This interferes seriously with the fine regulation, so that the carbon compression regulator can only be made use of in cases where 30 no very accurate regulation is required.

The present invention has for its object to provide a quick-acting regulator in which 40 the advantages of the mechanical simplicity of the vibrating regulator and of the carbon compression regulator are fully realized, while the electrical disadvantages of the same are avoided. According to the invention 45 a regulable non-inductive resistance is connected up in parallel to the vibrating or tremble contact of a regulator, which resistance can be adjusted between a minimum and a maximum value. As the regulable 50 resistance a carbon compression regulator is

preferably used, which by coacting with the vibrating contact allows of a fine regulation in direct dependence on the excitation of the generator.

In the constructional example shown in 55 our prior application Serial No. 280,287, from which the present application has been divided out, the vibrating contact and the carbon compression regulator are jointly controlled by the armature of a single electromagnet, but according to the present invention the two may be controlled independently of one another by separate electromagnetic means.

In the constructional example described 60 in our copending application Serial No. 280,287, the vibrating regulator is mechanically rigidly coupled to the carbon compression regulator, so that the two are synchronously controlled in dependence on the 65 magnitude of the excitation current of the generator. According to the present invention, instead of the two regulators being mechanically coupled the carbon compression regulator is independently controlled 70 by electromagnetic means in dependence on the excitation current of the generator flowing over the vibrating contacts, so that the metallic contacts of the vibrating regulator are relieved. The invention may be carried 75 into effect as shown in the accompanying drawing wherein *a* is the generator and *b* the excitation winding of the same. *r* is the regulator provided with an interrupter coil. *c*, *c*₁ are the vibrating contacts lying in the 80 excitation circuit. In parallel with the vibrating contacts is the carbon compression regulator *d*, the resistance value of which is regulated by the pressure of the armature *t* which is acted on by the electromagnet *s*. 85

Thus, should the entire excitation current flow over the vibrating contacts, the electromagnet *s* will be strongly energized and the armature *t* will exert a great pressure on the carbon column of the carbon compression regulator, the resistance value of the latter being consequently reduced. The voltage at the terminals of the generator would consequently rise. The vibrating regulator, however, immediately offers a 90 95 100

greater arc resistance, so that through a corresponding diminution in the attractive force of the electromagnet the pressure of the armature *t* on the carbon column is reduced, and the resistance value of the carbon compression regulator thereby increased. This cycle of operations is repeated automatically in dependence on the excitation current flowing over the vibrating contacts, so that the vibrating contacts are relieved by the parallel connected carbon compression regulator.

Having now described our invention, what we claim as new and desire to secure by Letters Patent is:

1. A quick acting regulator of the vibrating contact type including a pair of vibrating contacts in series with the magnitude to be regulated, an electromagnet for vibrating said contacts, a non-inductive resistance shunted across said vibrating contacts, and a second electromagnet arranged to vary said non-inductive resistance from a minimum to a maximum value in dependence upon the current flowing through the vibrating contacts.

2. A regulator as claimed in claim 1 wherein the said non-inductive resistance is of the compressible carbon plate type.

30 In testimony whereof we have signed our names to this specification.

HULDREICH MEYER-BERG.
ROBERT KELLER.
